US00D743091S

(12) **United States Design Patent**
Degrandis et al.

(10) **Patent No.:** **US D743,091 S**
(45) **Date of Patent:** **** Nov. 10, 2015**

(54) **RIPPLE DIFFUSER**

(71) Applicant: **ACOUSTICS FIRST CORPORATION**, Richmond, VA (US)
(72) Inventors: **James J. Degrandis**, Fredericksburg, VA (US); **Joseph E. Horner**, Richmond, VA (US); **C. Nicholas Colleran, Jr.**, Richmond, VA (US)

(73) Assignee: **ACOUSTICS FIRST CORPORATION**, Richmond, VA (US)

(**) Term: **14 Years**

(21) Appl. No.: **29/462,948**

(22) Filed: **Aug. 9, 2013**

(51) LOC (10) Cl. **26-99**

(52) U.S. Cl.

USPC **D26/122**; D26/125

(58) **Field of Classification Search**

USPC D26/9, 10, 12, 13, 15, 16, 24, 51, 61, D26/72, 76, 80, 81, 85, 86, 88, 90, 118, 119, D26/120, 128, 129, 138, 143, 144, 113, 122, D26/125; D13/180; D10/18, 21, 24, 25, 27, D10/28, 46, 93, 104, 106, 113, 114, 116.1, D10/121; D17/99

CLAIM

The ornamental design for the ripple diffuser, as shown and described.

DESCRIPTION

FIG. 1 is a top and left front perspective view of a first embodiment of a ripple diffuser;

FIG. 2 is a top and right front perspective view of the first embodiment;

FIG. 3 is a top and right rear perspective view of the first embodiment;

FIG. 4 is a top and left rear perspective view of the first embodiment;

FIG. 5 is a top plan view of the first embodiment;

FIG. 6 is a front side elevation view of the first embodiment;

FIG. 7 is a right side elevation view of the first embodiment;

FIG. 8 is a rear side elevation view of the first embodiment;

FIG. 9 is a left side elevation view of the first embodiment;

FIG. 10 is a bottom plan view of the first embodiment;

FIG. 11 is a bottom and left front perspective view of the first embodiment;

FIG. 12 is a bottom and right front perspective view of the first embodiment;

FIG. 13 is a bottom and right rear perspective view of the first embodiment;

FIG. 14 is a bottom and left rear perspective view of the first embodiment;

FIG. 15 is a top and left front perspective view of a second embodiment of the ripple diffuser;

FIG. 16 is a top and right front perspective view of the second embodiment;

FIG. 17 is a top and right rear perspective view of the second embodiment;

FIG. 18 is a top and left rear perspective view of the second embodiment;

FIG. 19 is a top plan view of the second embodiment;

FIG. 20 is a front side elevation view of the second embodiment;

FIG. 21 is a right side elevation view of the second embodiment;

FIG. 22 is a rear side elevation view of the second embodiment;

FIG. 23 is a left side elevation view of the second embodiment;

FIG. 24 is a bottom plan view of the second embodiment;

FIG. 25 is a bottom and left front perspective view of the second embodiment;

FIG. 26 is a bottom and right front perspective view of the second embodiment;

FIG. 27 is a bottom and right rear perspective view of the second embodiment; and,

FIG. 28 is a bottom and left rear perspective view of the second embodiment.

The broken lines of Embodiment 2 (FIGS. 15-28) of the drawing disclosure illustrate environmental structure and boundaries that form no part of the claimed design.
